UNITED STATES PATENT OFFICE.

CORYDON NORTON, OF ALBION, ASSIGNOR OF ONE-FOURTH TO ISAAC OPPENHEIMER, OF ERIE, PENNSYLVANIA.

WAGON WHEEL AND AXLE.

SPECIFICATION forming part of Letters Patent No. 246,334, dated August 30, 1881.

Application filed December 11, 1880. (No model.)

To all whom it may concern:

Be it known that I, CORYDON NORTON, a citizen of the United States, resident of Albion, in the county of Erie and State of Pennsylvania, have invented a new and useful Improvement in Wagon Wheels and Axles; and I do hereby declare the following to be a full, clear, and exact description thereof.

My invention relates to the construction of wagon wheels and axles; and it consists in providing the improvements hereinafter fully described and claimed.

My invention is shown in the accompanying drawings, as follows: Figure 1 is a vertical longitudinal section of the hub and thimbles, the axle being in elevation. Fig. 2 is an elevation view from the front of the hub, with the flange d' removed. Fig. 3 is a vertical longitudinal section of the collar C on the axle and its attaching-arm C'. Fig. 4 is an end view of the hub without showing the spokes or flange, and with the securing-nuts and washers removed.

The hub consists of a body, D, with flange d , formed of one piece of cast metal. Said flange is thick, and has sockets formed therein to receive the ends of the spokes, the form of which is shown in Fig. 2, and is such that the said sockets are narrowed midway between the periphery of the flange and the body or shell of the hub, giving an inward and an outward dovetail flare or angle, and forming a dovetail at the inner end of the socket. These sockets are all open on the side, and the spokes are set into them sidewise. A movable flange, d' , completes the hub. This sets against the open side of the spoke-sockets, and is firmly secured there by bolts F. The spokes may be set in their sockets with white lead or other cement, as desired.

If a spoke should be broken and it is desired to replace it, it can be done by removing the flange d' . If the hub should be broken, the spokes can be driven out and reset in a new hub without disturbing the rim of the wheel.

A is an iron or steel axle, and A' is the part thereof which enters the hub. B is the wood which commonly caps the iron part of the axle. The axle A A' is made square throughout its

length, except the screw-threaded nipple A'' 50 at the end.

C is a collar, and is made with an arm, C', extending therefrom, by which it is attached firmly at the proper point to serve as a shoulder. This attachment is made by a bolt or by 55 the clip, or by both. This collar forms the shoulder against which the inner end of the hub abuts. It and its arm C' are of one piece of metal, preferably malleableized cast-iron. The arm C', besides serving to hold the collar in 60 place, also serves as a splint on the axle, giving it additional strength at a point where the greatest strain comes upon it. The journal for the hub is formed by putting a thimble or thimbles on the part A' of the axle. The object of this is to get as large a bearing-surface as possible and still use a small axle, and also to be able to change the position of the thimble when one side becomes worn.

In Fig. 1 I show two thimbles, G and H, of 70 which G is of wood and H is of metal. The thimble G is properly a core, and it serves to obviate the use of so much iron as to give too much weight. It may, however, be dispensed with and the thimble H be made to fill the 75 whole space. Its use, however, will be found desirable, especially in large vehicles. The part A' of the axle is square, and the opening through the thimble is square; hence the thimble cannot revolve; but when worn by use on 80 one side it can be turned by removing and replacing it to as to present an unworn part at the bearing-point. There are two nuts used on the nipple A''. The nut N holds the thimble 85 in place, and is only unscrewed when it is desired to remove the thimble. The wheel is held in place by the washer W and the nut N', the washer W being made to fit over the nut N.

I am aware that a collar and strap similar in appearance to the collar C shown by me 90 has been used, (see Patent No. 73,340,) and in so far as the device serves to strengthen the axle at that point I claim nothing; but their use upon an axle which is square throughout and has its journal formed by a thimble slipped 95 on is a new and useful combination.

I am also aware that a wooden core or fillet has been used in the construction of iron hubs,

(see Patent No. 153,384;) but such a use has no relation to the use of a core or fillet of wood in the construction of the axle-journal, which constitutes my invention in that respect.

5 I am also aware that a hub has been made having spoke-sockets shaped the same as I here show and placed alternately on opposite sides of a flange extending from the shell of the hub; and this I do not claim; nor do I claim 10 simply a hub having sockets for spokes arranged in the same vertical plane and having a removable flange to hold them in place, as that form of hub is old; but

What I claim as new is—

15 1. A wagon-wheel hub consisting of a sheet or body and flange d , of one piece of metal, said flange d having double-dovetailed spoke-sockets formed in the inner side thereof, in combination with the movable flange d' and 20 bolts F, substantially as set forth.

2. The axle A A', the part A' being squared, as described, in combination with thimble H, having a squared opening for said part A', and the collar C, with attaching arm or strap C', substantially as described. ²⁵

3. The combination, with the axle A A', of the thimble H and wooden core G, substantially as and for the purposes set forth.

4. The combination, with the axle A A' and hub D, of the thimble H, nut N, washer W, ³⁰ and nut N', substantially as shown.

In testimony whereof I, the said CORYDON NORTON, have hereunto set my hand.

CORYDON NORTON.
